UNITED STATES PATENT OFFICE.

FRED A. CROCKER, OF LINCOLN, MAINE.

RATCHET-WRENCH.

SPECIFICATION forming part of Letters Patent No. 625,149, dated May 16, 1899.

Application filed January 10, 1898. Serial No. 666,197. (No model.)

To all whom it may concern:

Be it known that I, FRED A. CROCKER, a citizen of the United States, residing at Lincoln, in the county of Penobscot and State 5 of Maine, have invented a new and useful Ratchet-Wrench for the Purpose of Turning Nuts, Bolts, Screws, &c.; and I do hereby declare that the following is a full, clear, and exact description of my invention and the operation of the same, that will enable others skilled in the art to which it appertains to make and use the same.

Throughout the description reference is made to the accompanying drawings, in 15 which—

Figure 1 represents a plan of the upper side of my improved ratchet-wrench complete. Fig. 2 shows a plan of the under side of the same. Fig. 3 is a side view, partly in section, 20 cut vertically through the working parts of my device.

Similar letters of reference refer to correspondingly like parts of the device throughout the different figures.

25 The object of my invention is to produce an improved ratchet-wrench of simple construction adapted to be operated in either direction and have the ratchet portion made removable to allow a similar part with different 30 size wrench-openings to be interchanged therewith.

Referring to the drawings, A represents the wrench-lever, which is constructed with rounded edges for a portion of its length to 35 form the handle at one end, while its opposite end is widened sufficiently to have a hole bored transversely therethrough to receive the wrench-spool B. The wrench-spool is made long enough to project each side of the 40 lever A when inserted in the opening, and one end is enlarged sufficiently to allow cross-grooves to be cut therein to form ratchets into which the point of a dog enters to operate the same, as will hereinafter be described.

45 The opposite end of the wrench-spool B is of the same size as that portion within the opening in the lever, and where it extends through the latter is cut a groove e around its circumference, into which the end of a spring-latch 50 E enters for the purpose of retaining the spool in place.

The latch E is secured to slide longitudi-

nally on the lever A by means of screws i i, passing through slots in said latch and entering the lever. The heads of said screws being larger than the slots extend sufficiently over the surface of the latch to hold the latter firmly and prevent it from dropping off. A recess f' being made in the lever A, under the latch, within which is placed a spiral 60 spring s', and a pin or depression from the latch entering said recess in front of said spring allows the tension of the latter to force the latch forward and always keep its extremity within the groove in the extension of 65 the wrench-spool. To remove the spool, it is only necessary to draw back the latch E until its extremity is disengaged, when the spool can be drawn out of the opening and another inserted to be held in the same manner.

70 The center of the spool B at opposite ends is constructed with wrench-openings H and H' of different sizes, as shown in Figs. 1 and 3 of the drawings. Thus with a sufficient number of interchangeable spools with different wrench-openings most any sized nut can be turned with only one of my improved ratchet-wrenches.

Pivoted to the lever A in such position as to allow one of its extremities to engage the 80 ratchets in the wrench-spool is a double-ended pawl C, which is constructed in the shape of a lune and its pivotal screw attached at its mid-length near its concaved edge. Within the lever A, directly under the body of the 85 pawl and directly behind its pivotal connection, is a recess f, formed to receive a spiral spring, and depending from the pawl C is a pin s, entering the recess in front of the spring, which the latter engages to operate 90 the said pawl when working the wrench. The pin s being situated directly behind the pivotal attachment of the pawl C, when the latter is turned so that one of its extremities is in engagement to operate the ratchet the pin 95 will be at that side of the recess that the pawl is engaged, and thus out of line with the pivot of the latter. Consequently the force of the spring against the pin will tend to retain the said pawl in position to operate the ratchet 100 in one direction. To reverse or operate the ratchet in the opposite direction, it is only necessary to turn the pawl C so that its opposite end engages the ratchet, which move-

ment changes the pin *s* to the opposite side of the recess, where the spring will tend to keep this end engaged in the same manner as before mentioned.

5 Having thus described my invention, what I claim, and desire to secure by Letters Patent of the United States, is—

In a ratchet-wrench, a lever *A* having an enlarged end, a transverse opening in said enlarged end, a wrench-spool *B* removably secured in said transverse opening having formed at one end a ratchet and near its opposite end an annular groove *e*, a double-end pawl *C* constructed and arranged to engage

said ratchet with either end, centrally pivoted 15 to said lever *A*, a downwardly-projecting pin *s* secured to said pawl *C*, a recess *f* formed in said enlarged end of said lever *A* into which said pin *s* enters, a spring in said recess *f* engaging said pin *s* to hold either extremity of 20 said pawl *C* in engagement with said ratchet and a spring-pressed sliding latch *E* movably secured to said lever *A* engaging said wrench-spool *B*, substantially as described.

FRED A. CROCKER.
